(57) **CLAIM**

The ornamental design for a bait station, as shown and described.

DESCRIPTION

FIG. 1 is an isometric view of a bait station showing our design from the top and a side;

FIG. 2 is a top plan view of the bait station illustrated in FIG. 1;

FIG. 3 is a first side elevational view of the bait station illustrated in FIGS. 1 and 2;

FIG. 4 is a second side elevational view of the bait station illustrated in FIGS. 1 through 3 from the side of the bait station opposite the side illustrated in FIG. 3;

FIG. 5 is a third side elevational view of the bait station illustrated in FIGS. 1 through 4 from a side of the bait station orthogonal to the sides illustrated in FIGS. 3 and 4, the side of the bait station opposite the side illustrated in FIG. 5 being a mirror image thereof; and,

FIG. 6 is a bottom plan view of the bait station illustrated in FIGS. 1 through 5.
